UNITED STATES PATENT OFFICE

116,229

DESIGN FOR A BREAD BOX

William Garten, Baltimore, Md., assignor to Owens-Illinois Can Company, Wilmington,
Del., a corporation of Delaware

Application May 23, 1939, Serial No. 85,152

Term of patent 7 years

To all whom it may concern:

Be it known that I, William Garten, a citizen of the United States residing at Baltimore, in the State of Maryland, have invented a new, original, and ornamental Design for a Bread Box, of which the following is a specification, reference being had to the accompanying drawing, forming a part thereof.

In the drawing the figure is a perspective view of a bread box showing my new design. Both ends of the bread box have substantially the same appearance as the end shown. The flower-like surface ornamentation appears on the front only, while the stripe decoration continues down the rear wall.

I claim:

The ornamental design for a bread box, substantially as shown and described.

WILLIAM GARTEN,
